UNITED STATES PATENT OFFICE.

JOHN P. NISSEN, OF STAPLETON, NEW YORK, ASSIGNOR TO ONEIDA KNITTING COMPANY, INC., OF PHILADELPHIA, PENNSYLVANIA, A CORPORATION OF MASSACHUSETTS.

STOCKING.

1,142,774.

Specification of Letters Patent. Patented June 8, 1915.

Application filed September 30, 1914. Serial No. 864,245.

To all whom it may concern:

Be it known that I, JOHN P. NISSEN, a citizen of the United States, residing at Stapleton, in the county of Richmond and 5 State of New York, have invented new and useful Improvements in Stockings, of which the following is a specification.

The present invention relates more particularly to knitted hosiery, and the primary 10 object is to provide an article of this character, in which raveling, caused by the strain of the garter, and consequent breakage of the loops, is prevented, said reinforcement not materially interfering with the desired 15 elasticity at the upper end of the stocking, and constituting, in addition, a marker for sewing the welt, so that the finishing of the stocking can be accomplished very expeditiously, and a more uniform output secured. 20 An embodiment of the invention is illustrated, somewhat diagrammatically, in the accompanying drawings, wherein:—

Figure 1 is a side elevation of a stocking with the improvement. Fig. 2 is a detail 25 sectional view through the upper portion of the stocking. Fig. 3 is a diagram illustrating the method of making the reinforcement and of producing a finer body section.

Similar reference numerals designate cor- 30 responding parts in all the figures of the drawings.

In the embodiment disclosed, the stocking is designated, generally, by the reference numeral 4, and may be of any form or mate- 35 rial desired, being a tubular knitted fabric. The upper end portion of the body of the stocking, which constitutes the welt section, is designated 5, and is of relatively loose open loops to secure material elasticity. At 40 a point to which the end edge of the welt is secured to the body, a reinforcement is formed in said body, said reinforcement being shown at 6. The remainder of the body, designated 7, is much finer than the 45 fabric at and above the reinforcement, being formed by tightening the knitting ma- chine.

In the form shown, and referring particu- 50 larly to Fig. 3, the welt section 5 is pro- duced by the usual method of knitting a thread 8 into rows of interlaced loops. At the point where the reinforcement is made, an extra thread 9 is spliced in for the width of the reinforcement, usually about half an

inch, though this width can be varied if 55 desired. The reinforcing thread is then dropped and the knitting of the thread 8 is continued, to produce the body of the stocking, the machine being tightened a few rows below the reinforcement as shown at 8^a in 60 Fig. 3, thereby producing a much finer fabric.

The welt section is folded upon itself as shown in Fig. 2 by sewing or otherwise securing the free edge of said welt section to the upper marginal portion of the reinforce- 65 ment, as illustrated at 10.

It will be obvious that the reinforcement strengthens the fabric of the stocking, and yet does not materially interfere with the desired elasticity thereof. Said reinforce- 70 ment furthermore furnishes a heavier body for the sewing of the welt, thus eliminating to a material degree, the danger of breaking the thread and the consequent raveling, caused by the strain of the garters which are 75 fastened to the welt. Moreover, it acts as a marker upon the fabric, which enables the operator to have all the tops of one width, as it indicates exactly the line where the sewing is to be done, thus expediting the 80 work of finishing, and securing a uniform output. In addition to this, it furnishes a definite mark in the stocking, from which on, by tightening the machinery, a much finer fabric is produced below the reinforcement. 85 In other words, it enables the operator to procure a tighter fabric in the lower part of the stocking below the welt, where it is wanted, and a looser fabric in the top of the stocking where more elasticity is needed. 90

From the foregoing, it is thought that the construction, operation and many advantages of the herein described invention will be apparent to those skilled in the art, without further description, and it will be un- 95 derstood that various changes in the size, shape, proportion and minor details of construction may be resorted to without departing from the spirit or sacrificing any of the advantages of the invention.

Having thus fully described my invention, what I claim as new and desire to secure by Letters Patent, is:—

1. In an article of the character set forth, a knitted body having a knitted reinforced portion and a welt secured to the reinforce- 105 ment.
2. In an article of the character set forth,

a knitted body having a reinforcement knitted thereinto, and a welt comprising a margin of the body doubled upon itself and having its edge secured to the reinforcement.

5 3. In an article of the character set forth, a tubular knitted body, a tubular reinforcement knitted thereinto, and a welt comprising a margin of the body doubled upon itself and having its edge secured to the upper portion of the reinforcement.

10 4. In an article of the character set forth, a knitted body, an extra thread knitted into a portion of the same, forming a reinforcement, and a welt comprising a margin of the body doubled upon itself and secured to the reinforcement.

15 5. In an article of the character set forth, a tubular knitted body, an extra thread knitted into a portion of the same at a distance from its edge, forming a tubular reinforcement in the body, and a tubular welt com-

prising the portion of the body between the reinforcement, and the end of said body doubled upon itself and secured to the upper marginal portion of the reinforcement.

25

6. An article of the character set forth, comprising a tubular loose knitted elastic welt section, a tubular reinforcement adjacent to the welt section, comprising a knitted portion of heavier material and a knitted body section of smaller loops adjacent to the reinforcement, said welt section being doubled upon itself and having its free end secured to the upper marginal portion of the reinforcement.

30

In testimony whereof I have hereunto set my hand in presence of two subscribing witnesses.

JOHN P. NISSEN.
